UNITED STATES PATENT OFFICE

WILLIAM P. DAY, OF CLEVELAND HEIGHTS, OHIO, ASSIGNOR TO THE INTERNATIONAL STEEL TIE COMPANY, OF CLEVELAND, OHIO, A CORPORATION OF OHIO

RAILROAD TIE

Application filed May 31, 1929. Serial No. 367,257.

This invention relates generally to a composite railroad tie or stringer and more particularly to a cross tie of the non-insulated type which is adapted to be embedded in the concrete of a street or road in such a manner that the top of the rail is disposed substantially level with the surface of the street or road.

The main object of the invention is to provide a simple, durable and efficient rail support which is made of few parts which are readily assembled and disassembled and which is well adapted to quantity production at comparatively low cost.

A further object of the invention is to provide a cross tie construction which consists essentially of a pair of angle bars each of which has a slot in the opposite ends thereof and into which rail plates are secured preferably by welding.

20 A further object of the invention is to provide a cross tie construction which may be shipped in knock-down or disassembled condition and then assembled at the track side or any other convenient place.

25 A still further object of the invention is to provide a strong and dependable cross tie construction in which the angle bars are bent upwardly at the central portion thereof and disposed in a plane considerably above the end portions thereof whereby to reinforce the upper slab of concrete between the rails.

30 A still further object of the invention is to provide a cross tie construction of the character described in which the cross angle bars are bent upwardly between the rails so as to require less concrete between the rails and which is also provided with means for securely anchoring the rails to the central portion of the cross bars.

40 Further and more limited objects of the invention will appear as the description proceeds and by reference to the accompanying drawing in which Fig. 1 is a top plan view of my improved tie construction; Fig. 2 is a view in side elevation of the tie shown in Fig. 1; Fig. 3 is a view in end elevation of the tie shown in Figs. 1 and 2 but on a smaller scale; Fig. 4 is a vertical sectional view of a portion of a roadbed having my improved tie arranged therein and Fig. 5 is a view similar

to Fig. 4 disclosing a modified form of tie construction in which the central portions of the angle bars are deflected upwardly and disposed in a plane above the end portions thereof so as to reinforce the upper slab of 55 concrete between the rails.

Referring now to the drawings the reference characters 1 and 2 designate a pair of spaced parallel angle bars or cross beams. The opposite ends of the angle bars 1 and 2 60 are provided with slots 3, 4 and 3^a, 4^a respectively. Connecting the angle bars 1 and 2 and disposed at opposite ends thereof are rail plates 5 and 6 which fit within the slots, as shown most clearly in Figs. 1 and 2. The rail plates 5 and 6 are preferably welded to the angle bars, as shown most clearly in Fig. 2. The rail plates 5 and 6 are each provided with oppositely disposed pairs of T-shaped slots 7, 8 and 7^a, 8^a. These slots are adapted 65 to receive the rail clamps therein for securing rails to the rail plates in a manner to be hereinafter described. The slots 3, 3^a and 4, 4^a are cut on slight angle so that when the rail plates are secured in place they will be disposed at a slight angle to each other so that when the rails are secured thereto they will slope inwardly slightly in order to conform to the contour of the wheels. The rail plates 70 preferably have portions 9 and 9^a cut therefrom and bent downwardly therefrom as shown, which portions serve to firmly embed the tie in the concrete. The tie may be shipped in the disassembled or knock-down condition so as to occupy less space in shipping and may be assembled at the track side or at any other convenient place.

85 In forming the road bed a trench is provided in which the portions immediately beneath the rails are somewhat deeper than the remaining portion. The ties are assembled as hereinbefore described and arranged within the trench and supported upon blocks at about the position shown in Fig. 4. The rails are then secured to the rail plates by 90 means of the rail clamps 10, 10^a and 11, 11^a. A layer of concrete is then poured up to about the level indicated by the line a—a in Fig. 4. Suitable forms are inserted to provide drain 95 openings 12 and 13. After this layer of con- 100

crete has hardened and set, the upper surface of the roadbed may be laid and may be of any suitable material. If the road surface is to be formed of paving stones, the stones are laid in the manner well known to those skilled in the art leaving a slight space along both sides of each rail. This space is then filled with bituminous concrete indicated at 14 in Fig. 4. This material consists of slag and crude asphalt in about the following proportions: 3 parts fine slag, 2 parts coarse slag and 1 part crude asphalt. This material is waterproof and prevents water from seeping in adjacent or along the rail. The drain holes are filled with gravel or cinders or other suitable material which permits the water to drain off below the foundation. It is of course understood that drain holes may be provided along one or both sides of the rails.

In Fig. 5 there is disclosed a slightly modified form of my invention. This form of the invention is substantially identical with the form of the invention shown in Figs. 1 to 4 inclusive except that the central portions 25 of the angle bars or cross beams are bent upwardly so as to be disposed in a plane above the end portions thereof. The rail plates are secured to the angle bars as described in connection with Figs. 1 to 4 inclusive. Disposed adjacent the opposite ends of each of the angle bars are tie rods 15 and 16. The inner ends of the tie rods are preferably welded to the central portion of the angle bars as shown at 17 and 18. The opposite 35 ends of the tie rods are threaded and are adapted to project through openings in the rails and to be secured thereto by nuts 19, 20 and 19^a, 20^a. These tie rods serve to strengthen and reinforce the construction as 40 a whole and to firmly secure the rails against displacement. According to the preferred construction the central portions of the angle bars are disposed in a plane about two inches above the end portions thereof.

This construction enables a thinner layer 45 of concrete to be used between the rails and provides a reinforcement for the comparatively thin upper layer of material. It also effects a saving of concrete amounting to approximately 350 cubic yards per mile which at present prices will amount to about \$3,000.00 per mile.

Various changes may be made in the details of construction and in the manner of 55 assembling and securing the various parts in place without departing from the spirit of my invention. Moreover, it should be understood that my invention is not limited to any particular type of road surface or foundation as different materials may be used according to the nature of the track and according 60 to the load the track is intended to withstand. It is therefore understood that my invention is limited only in accordance with 65 the scope of the appended claims.

Having thus described my invention, what I claim is:

1. A railroad tie construction of the character described comprising a pair of spaced, parallel angle bars, each of said angle bars having slots in the opposite ends thereof respectively, a pair of rail plates connecting said pair of angle bars respectively and disposed within said slots, rail clamps carried by said plates and adapted for securing a rail thereto. 70

2. A railroad tie construction of the character described comprising a pair of spaced, parallel angle bars, each of said angle bars having slots in the opposite ends thereof respectively, a pair of rail plates connecting said pair of angle bars respectively and disposed within said slots, rail clamps carried by said plates and adapted for securing a rail thereto, said rail plates being welded to 85 said angle bars. 80

3. A railroad tie of the character described comprising a pair of spaced parallel beams extending substantially at right angles to the track, each of said beams having slots in the opposite ends thereof, rail plates connecting said pair of beams at the opposite ends thereof and disposed within said slots respectively, the central portion of said beams being disposed in a plane above the end portions 90 thereof. 95

4. A railroad tie of the character described comprising a pair of spaced parallel beams extending substantially at right angles to the track, each of said beams having slots in the opposite ends thereof, rail plates connecting said pair of beams at the opposite ends thereof and disposed within said slots respectively, the central portion of said beams being disposed in a plane above the end portions 100 thereof, means for securing a rail to said rail plates respectively and means for connecting the central portions of said beams to the rails 105 respectively.

5. A railroad tie of the character described comprising a pair of spaced parallel beams extending substantially at right angles to the track, each of said beams having slots in the opposite ends thereof, rail plates connecting said pair of beams at the opposite ends thereof and disposed within said slots respectively, the central portion of said beams being disposed in a plane above the end portions thereof, means for securing a rail to said rail plates respectively and means for connecting the central portions of said beams to the rails 110 respectively, 115

6. A rail supporting structure of the character described comprising a concrete base, a tie supported by said concrete base and having its central portion deflected upwardly and disposed in a plane considerably above the end portions thereof, and a course of con- 120 125 130

crete disposed above said tie and covering both the end portions and central portion of the tie.

7. A rail supporting structure of the character described comprising a concrete base, a tie supported by said concrete base and having its central portion deflected upwardly and disposed in a plane considerably above the end portions thereof, and a course of concrete disposed above said tie and covering both the end portions and central portion of the tie, said tie consisting of a pair of rail plates and a pair of spaced, parallel angle bars, the opposite ends of which are slotted and adapted to receive the rail plates therethrough, and means carried by the rail plates for securing rails thereto respectively.

8. A rail supporting structure of the character described comprising a concrete base, a tie supported by said concrete base and having its central portion deflected upwardly and disposed in a plane considerably above the end portions thereof, and a course of concrete disposed above said tie and covering both the end portions and central portion of the tie, said tie consisting of a pair of rail plates and a pair of spaced, parallel angle bars, the opposite ends of which are slotted and adapted to receive the rail plates therethrough, and means carried by the rail plates for securing rails thereto respectively, and means connecting the central portion of said angle bars with the rails.

9. A rail supporting structure of the character described comprising a concrete base, a tie supported by said concrete base and having its central portion deflected upwardly and disposed in a plane considerably above the end portions thereof, and a course of concrete disposed above said tie and covering both the end portions and central portion of the tie, said tie consisting of a pair of rail plates and a pair of spaced, parallel angle bars, the opposite ends of which are slotted and adapted to receive the rail plates therethrough, means carried by the rail plates for securing the central portion of said angle bars with the rails, said means consisting of tie rods disposed adjacent the ends of each of said angle bars.

50 10. A rail supporting structure of the character described comprising a foundation consisting of a layer of concrete, the central portion of which is considerably thinner than the end portions thereof, a tie supported by said foundation and having its central portion deflected upwardly in conformity with said layer of concrete and a layer of road forming material disposed over said tie and covering both the central portion and the end portions of the tie.

11. A rail supporting structure of the character described comprising a foundation consisting of a layer of concrete, the central portion of which is considerably thinner than the end portions thereof, a tie supported

by said foundation and having its central portion deflected upwardly in conformity with said layer of concrete and a layer of road forming material disposed over said tie and covering both the central portion and the end portions of the tie, said tie consisting of a pair of rail plates and a pair of spaced parallel angle bars the opposite ends of which are slotted and receive the rail plates therethrough, and means carried by the rail plates for securing the rails thereto respectively.

12. A rail supporting structure of the character described comprising a foundation consisting of a layer of concrete, the central portion of which is considerably thinner than the end portions thereof, a tie supported by said foundation and having its central portion deflected upwardly in conformity with said layer of concrete and a layer of road forming material disposed over said tie and covering both the central portion and the end portions of the tie, said tie consisting of a pair of rail plates and a pair of spaced parallel angle bars the opposite ends of which are slotted and receive the rail plates therethrough, means carried by the rail plates for securing the rails thereto respectively, and means for connecting the central portion of the angle bars to the rails.

13. A rail supporting structure of the character described comprising a foundation consisting of a layer of concrete, the central portion of which is considerably thinner than the end portions thereof, a tie supported by said foundation and having its central portion deflected upwardly in conformity with said layer of concrete and a layer of road forming material disposed over said tie and covering both the central portion and the end portions of the tie, said tie consisting of a pair of rail plates and a pair of spaced parallel angle bars the opposite ends of which are slotted and receive the rail plates therethrough, means carried by the rail plates for securing the rails thereto respectively, and means for connecting the central portion of the angle bars to the rails, said means comprising tie rods disposed adjacent the ends of each of said angle bars.

14. A rail supporting structure of the character described comprising a foundation consisting of a layer of concrete the central portion of which is considerably thinner than the end portions thereof, a tie supported by said foundation and having its central portion deflected upwardly in conformity with said layer of concrete and a layer of road forming material disposed over said tie and covering both the central portion and the end portions of the tie, said tie consisting of a pair of rail plates and a pair of spaced parallel angle bars the opposite ends of which are slotted and receive the rail plates therethrough, means carried by the rail plates for

securing the rails thereto respectively, and means for connecting the central portion of the angle bars to the rails, said means comprising tie rods disposed adjacent the ends of each of said angle bars, the slots in said angle bars being so disposed that said rail plates will be disposed at a slight angle with respect to each other.

15. A railroad tie construction of the character described comprising a pair of spaced parallel angle bars, each of said angle bars having slots in the opposite ends thereof respectively, a pair of rail plates connecting said pair of angle bars at the opposite ends thereof and disposed within said slots respectively, the central portions of each of said angle bars being disposed in a plane above the end portions thereof, and means for securing a rail to said rail plates respectively.

20. 16. A railroad tie construction of the character described comprising a pair of spaced parallel angle bars, each of said angle bars having slots in the opposite ends thereof respectively, a pair of rail plates connecting said pair of angle bars at the opposite ends thereof and disposed within said slots respectively, the central portion of each of said angle bars being disposed in a plane above the end portions thereof, and means for securing a rail to said rail plates respectively, tie rods disposed adjacent the end portions of each of said angle bars, each tie rod having one end connected with said central portion and its opposite end adapted for connection with a rail.

25. 17. A railroad tie construction of the character described comprising a pair of spaced parallel angle bars, each of said angle bars having slots in the opposite ends thereof respectively, a pair of rail plates connecting said pair of angle bars at the opposite ends thereof and disposed within said slots respectively, the central portion of each of said angle bars being disposed in a plane above the end portions thereof, and means for securing a rail to said rail plates respectively, tie rods disposed adjacent the end portions of each of said angle bars, each tie rod having one end connected with said central portion and its opposite end adapted for connection with a rail, said rail plates being welded to said angle bars and disposed at an angle to each other.

30. 18. A railroad tie construction of the character described comprising a pair of spaced parallel angle bars, each of said angle bars having slots in the opposite ends thereof respectively, a pair of rail plates connecting said pair of angle bars at the opposite ends thereof and disposed within said slots respectively, the central portion of each of said angle bars being disposed in a plane above the end portions thereof, and means for securing a rail to said rail plates respectively, tie rods disposed adjacent the end portions

of each of said angle bars, each tie rod having one end connected with said central portion and its opposite end adapted for connection with a rail, said rail plates being welded to said angle bars and disposed at an angle to each other, the tie rods being welded to the central portions of the angle bars.

In testimony whereof, I hereunto affix my signature.

WILLIAM P. DAY.
